UNITED STATES PATENT OFFICE.

WILLIAM E. HASKELL, OF PHILADELPHIA, PENNSYLVANIA.

ORGAN.

SPECIFICATION forming part of Letters Patent No. 734,261, dated July 21, 1903.

Application filed February 25, 1901. Serial No. 48,770. (No model.)

To all whom it may concern:

Be it known that I, WILLIAM E. HASKELL, of Philadelphia, in the State of Pennsylvania, have invented certain new and useful Improvements in Organs, whereof the following is a specification, reference being had to the accompanying drawings.

My invention relates generally to the members of an organ which distribute the wind and control the admission thereof to the sounding devices.

My invention comprises improvements in the construction and relative arrangement of the soundboard, the wind-chest, and the pneumatic-levers which control the admission of wind through the soundboard to the sounding devices hereinafter more definitely specified and claimed.

The soundboard of an ordinary pipe-organ consists of a single horizontal panel in which the sound-pipes are seated, which panel forms the top of what is termed the "wind-chest," whose bottom consists of a single panel called the "bottom board." Said soundboard and bottom board are connected by vertical partition-bars which divide the wind-chest between said boards in a plurality of wind-chambers each common to a series or register of sound-pipes. Extending longitudinally within said partition-bars are wind-ducts leading to pneumatic-bellows levers fixed in vertical position upon said partition-bars in the respective wind-chambers and arranged to control the admission of wind from said chambers to the respective sound-pipes.

In the practice of my invention I construct a sounding-board of two series of narrow slats, the respective series being horizontally disposed at right angles to each other in such latticed relation that air-spaces exist between the adjoining slats in each series, which arrangement permits the individual slats to expand and contract independently without disturbance of the required relation of the component parts of the board. Moreover, the air-ducts leading to the pneumatic-levers are formed in said horizontal slats instead of in the vertical partition-bars, as heretofore.

The ordinary pneumatic-bellows levers being fixed in an ordinary wind-chest, as aforesaid, in vertical position upon the partition-bars, an essential element of such a lever is a

spring operatively connected with its bellows to expand the latter. It is found in practice that in each operation of such a spring-provided bellows to open the valve with which it is connected there is an appreciable delay due to the fact that the wind-pressure exerted upon the bellows must be continued without movement of the lever until not only the inertia of the latter, but also the stress of the spring, is overcome. As hereinafter described, in the practice of my invention the pneumatic-bellows levers are so constructed and arranged as to be operative without the employment of springs, being so balanced as to respond instantly to either internal or external pressure.

In the accompanying drawings, Figure 1 is a sectional view of a partial organ conveniently embodying my invention. Fig. 2 is an enlarged sectional view of the soundboard, wind-chest, &c., shown in Fig. 1. Fig. 3 is a sectional view taken on the line 3 3 in Figs. 1 and 2. Fig. 4 is a sectional view taken on the line 4 4 in Fig. 3. Fig. 5 is fragmentary plan view showing the latticed construction of the soundboard.

Referring to Fig. 1, A is the manual, whose digitals *a* are respectively connected with the manual-action valves *b*. Said valves control the admission of wind from the manual-action box B through the ducts *c* to the respective primary pneumatic-bellows C. Each of said primary pneumatics C is provided with a pressure-valve *c'* and an exhaust-valve *c''*, coupled by a rod *c'*, to control the admission of wind from the primary valve-box D through the respective conduits *d* to the intermediate pneumatic-bellows *e*. Said pneumatics *e* are each provided with a pressure-valve *e'* and an exhaust-valve *e''*, coupled by a rod *e'* to control the admission of wind from the intermediate valve-box E to the soundboard F. Said soundboard F comprises a series of parallel top slats *f* and a series of parallel bottom slats *f'*, fixed in right-angular latticed relation, as indicated in the several figures, the adjoining slats in each series being slightly separated to permit of independent contraction and expansion of the respective slats. The bottom slats *f'* are provided with internal wind-ducts *f''*, which are respectively in communication with the valve-box E by the openings *f'''* and comprise branch open-

ings f^4 , extending through the bottom of the soundboard, and the several pneumatic-bars $g^1 g^2 g^3 g^4$. Said bars are fixed to the soundboard parallel with the top slats f and form the respective tops of the separate unit wind-boxes $G^1 G^2 G^3 G^4$, which constitute the wind-chest G .

The sound-pipes in the registers $H' H^2 H^3 H^4$ are provided with individual seats h in the top slats f of the soundboard F , and said pipes are respectively connected with the wind-boxes by the ports $h' h^2 h^3 h^4$, which extend from said seats through the top and bottom slats ff' and pneumatic-bars $g^1 g^2$, &c., into the respective wind-boxes $G^1 G^2$, &c. The pneumatic-bars $g^1 g^2 g^3 g^4$ respectively support the pneumatic-levers $I' I^2 I^3 I^4$ in horizontal position on the under side of the soundboard F and within the respective wind-boxes G^1 , &c. Each of said levers comprises a pneumatic-bellows whose cheek-piece i is fixed in registry with the respective duct-opening f^4 and a lever cheek-piece i' , hingedly connected to said fixed cheek-piece by a flexible inclosure i^2 . Each of said levers also comprises an arm i^3 , fixed upon the movable cheek-piece i' and provided at its extremity with a valve i^4 , in registry with the respective valve-ports $h' h^2$, &c.

The wind-chest G projects beyond the sounding-board F , as shown in Fig. 3, and supports the register stop-box J , which is connected with the supply of compressed air by the wind-trunk K . The admission of wind from said stop-box J to the respective units G^1, G^2, G^3 , and G^4 of the wind-chest is separately effected by the respective stop-pneumatic bellows J', J^2, J^3 , and J^4 , each of said pneumatics being provided with a pressure-valve j' and an exhaust-valve j^2 , coupled by a rod j^3 . Said stop-pneumatics J', J^2, J^3 , and J^4 , are independently connected with the primary stop-valve box L by means of the respective wind-conduits $L' L^2 L^3 L^4$, and the admission of wind to said conduits L' , &c., is effected by respective valve-levers m , each provided with a pressure-valve m' , and an exhaust-valve m^2 , coupled by a valve-rod m^3 , said levers m being arranged to be independently controlled by the respective digitals $n' n^2$, &c., of the stop-manual N .

The operation of the device above described is as follows: It being desired to use the register of pipes H' , the digital n' of the stop-manual N is depressed, as indicated in Fig. 1, which opens the conduit L' to the atmosphere and permits the stop-pneumatic J' to be collapsed, as shown in Fig. 4, by the wind within the box J , thus admitting the wind to the wind-chest box G' common to said register H' . The pneumatic-pressure thus produced in the box G' being external to the pneumatic-lever I' is balanced by the pneumatic-pressure within the bellows of said lever, while said bellows remains in communication with the wind-box E by the duct f^2 , &c. However, if any one of the digitals a in the manual A is depressed

the corresponding manual-action valve b is uplifted, wind is admitted beneath the respective primary pneumatic C , and its valve c^2 is closed and its valve c' opened, admitting wind from the primary valve-box D to the respective intermediate pneumatic e , thereby closing its valve e' and opening its valve e^2 , which opens the corresponding duct f^2 to the atmosphere, so that the bellows of the respective lever I' is instantly collapsed and opens the respective port h' leading to the particular pipe of the register H' corresponding to the digital a depressed, thereby causing that pipe to speak. To terminate the action of said pipe, the depressed digital a is released, the valve b is closed, the pressure falls within the respective duct c by means of the escape of wind from the exhaust-vent c^4 leading from each duct to the atmosphere, and the pneumatic C is collapsed by the wind-pressure upon the valve c' within the box D , thus closing said valve c' and simultaneously opening the valve c^2 . Opening of the valve c^2 permits the pressure in the intermediate pneumatic e to escape, and said pneumatic is collapsed by the pressure within the intermediate valve-box E , thereby opening the valve e' and simultaneously closing the valve e^2 , so that pressure is admitted to the bellows of the lever I' , and the latter gravitates to its normal position, wherein its valve i^4 closes the port h' leading to said pipe.

The embodiment of my invention which I have illustrated comprises an automatic playing device O , consisting of a wind-casing O' , containing the tracker-bar o' , which is provided with apertures equal in number to the digitals of the manual A , which apertures are respectively connected by the conduits o with the respective ducts c . Said casing O' also contains the rollers $P P'$, which cause the traverse of a perforated sheet of fabric Q over the tracker-bar o' to admit wind to operate any selected sound-pipe, as will be readily understood. However, I do not desire to limit myself to the particular embodiment of my invention which I have illustrated, as it is obvious that various modifications may be made therein without departing from the essential features of my invention.

I claim—

1. In an organ, the combination with a soundboard, comprising separate top and bottom slats relatively fixed in right-angular latticed relation; of a wind-chest, comprising a series of wind-boxes independently secured upon the bottom of said soundboard respectively parallel with said top slats; wind-ducts in said bottom slats opening through the lower side thereof in registry with the respective wind-boxes; sound-pipe seats in said top slats; valve-ports extending from said sound-pipe seats through said top and bottom slats, in registry with the respective wind-boxes; pneumatic-levers hingedly secured in horizontal position within the respective wind-boxes; bellows upon the respective levers

fixed in communication with said duct-openings; and valves fixed upon the respective levers in registry with said ports; each lever being so arranged as to open its respective 5 valve-port when the external pressure on the lever-bellows exceeds the internal pressure thereon, and to close said port when the internal and external pressures upon the lever-bellows are equalized, substantially as set 10 forth.

2. In an organ, the combination with a soundboard comprising separate top and bottom slats relatively fixed in right-angular latticed relation; of a wind-chest secured upon 15 the bottom of said soundboard; wind-ducts in said bottom slats opening through the lower side thereof; sound-pipe seats in said top slats; valve-ports extending from said pipe-seats through said top and bottom slats to 20 said wind-chest; pneumatic-levers hingedly secured in horizontal position within said wind-chest; bellows upon the respective levers fixed in communication with said duct-openings; and valves fixed upon the respective 25 levers in registry with said ports, substantially as set forth.

3. In an organ, the combination with a soundboard comprising separate top and bottom slats relatively fixed in right-angular latticed relation; of a wind-chest comprising a 30 series of wind-boxes independently secured upon the bottom of said soundboard; wind-ducts in said soundboard opening through the lower side thereof in registry with the respective 35 wind-boxes; sound-pipes seated in the top of said soundboard; valve-ports extending from said sound-pipe seats through said soundboard in registry with the respective wind-boxes; pneumatic-levers hingedly 40 secured in horizontal position within the respective wind-boxes; bellows upon the respective levers fixed in communication with said duct-openings; and valves fixed upon the respective levers in registry with said ports, 45 substantially as set forth.

4. In an organ, the combination with a soundboard comprising separate top and bot-

tom slats relatively fixed in right-angular latticed relation; of a wind-chest comprising a series of wind-boxes independently secured 50 upon the bottom of said soundboard, respectively parallel with said top slats, substantially as set forth.

5. In an organ, the combination with a soundboard comprising a series of separate 55 parallel top slats and a series of separate parallel bottom slats, fixed to said top slats in right-angular latticed relation therewith; of wind-ducts extending within said bottom slats and opening through the lower side thereof; sound-pipe seats in said top slats; and valve-ports extending from said seats through both the top and bottom slats, substantially as set forth.

6. In an organ, the combination with a 65 soundboard comprising separate top and bottom slats relatively fixed in right-angular latticed relation; of a wind-chest in operative relation with said soundboard, substantially as set forth.

7. In an organ, the combination with a soundboard comprising a series of separate top slats and a series of bottom slats; the two series being fixed together in right-angular latticed relation; of a wind-chest secured 75 upon the bottom of said soundboard, substantially as set forth.

8. In an organ, the combination with a soundboard, comprising separate top and bottom slats relatively fixed in right-angular latticed relation; of a plurality of registers of sound devices seated in said board; and a wind-chest comprising a plurality of independent wind-boxes in communication with the respective registers, substantially as set 85 forth.

In testimony whereof I have hereunto signed my name, at Philadelphia, Pennsylvania, this 21st day of February 1901.

WILLIAM E. HASKELL.
